EARTH MOVING VEHICLE

Robert E. Burrus, Buchanan, Frederick Gordon Mackay,
Detroit, and William H. Armstrong, Royal Oak, Mich.,
assignors to Clark Equipment Company, a corporation
of Michigan

Application December 22, 1953, Serial No. 28,166

Term of patent 14 years

(Cl. D14—3)

FIG. 1

FIG. 2

FIG. 3

FIG. 4

FIG. 5

Fig. 1 is a front end perspective view of an earth moving vehicle, showing our new design;

Fig. 2 is a rear end perspective view of the earth moving vehicle;

Fig. 3 is a side elevational view of the earth moving vehicle;

Fig. 4 is a front elevational view of the vehicle; and

Fig. 5 is a rear elevational view of the vehicle.

The dominant features of our design reside in the portions illustrated in solid lines.

We claim:

The ornamental design for an earth moving vehicle, as shown and described.
